SUPERHETERODYNE RECEIVER

Kurt Schlesinger, Berlin, Germany, assignor to
 Radioaktiengesellschaft D. S. Loewe, Berlin-
 Steglitz, Germany

Application March 5, 1936, Serial No. 67,343
 In Germany March 12, 1935

10 Claims. (Cl. 250—20)

The present invention relates to receivers employing locally generated oscillations and its main object is to prevent radiation of local oscillations, especially when the local oscillator operates on a short or ultra-short wave.

In such receivers there is considerable danger of radiation because the coupling capacity between electrodes of the mixing valve is sufficient at very high frequencies to introduce a disturbing coupling between the antenna and the oscillator.

According to the invention, in a radio receiver employing locally generated oscillations for beating with oscillations collected by the antenna, radiation of the locally generated oscillations from the antenna is prevented by means of a neutralizing circuit.

Embodiments of the invention will now be described, by way of example only, reference being made to the drawings comprising Figs. 1-4.

20 Fig. 1 shows diagrammatically the frequency changing circuit of a superheterodyne receiver;

Fig. 2 is a more constructional embodiment employing a circuit similar to that of Fig. 1, and

Figs. 3 and 4 are modifications of the circuit of

25 Fig. 1.

Reference will first be made to Fig. 1 which shows the frequency changing circuit of a superheterodyne receiver comprising a mixing valve 4 and an oscillatory valve 8; these two valves may be combined in a single envelope. The antenna 1 is connected through a very small condenser 2 of about 1 cm. to the control grid 3 of the mixing valve 4 whose cathode 5 is earthed. A screen grid 6 serves to screen the control grid 3 from the oscillation grid 7. Two or more screen grids may be provided. Furthermore, a screen grid 32 may be arranged between anode 31 and oscillatory grid 7. This oscillation grid 7 is directly connected to the grid (or alternatively the anode) of the triode 8. The triode 8, whose cathode 9 is likewise earthed, produces the local oscillations in conjunction with a circuit comprising condenser 10 and inductance 11. The circuit is so chosen that, in addition to the oscillation potential applied to electrode 7 of the mixing hexode 4, there is always present a small oscillation potential which is opposite in phase to that of the former.

Even when the antenna is completely shielded from all other parts of the receiver it still remains coupled to the oscillation circuit via the inter-electrode capacities of valve 4.

According to the applicant's observations, the disturbing radiation produced by superheterodyne receivers is primarily due to the capacity

between the control grid 3 and the oscillation grid 7. Owing to the presence of the screen grid 6, this capacity amounts in practice to only about 0.1 cm. In spite of this small value a disturbing radiation, which increases with increase in size 5 of the antenna 1, takes place when the local oscillations are of very high frequency, e. g. in the case of ultra-short waves of 7 m. length the capacitive reactance of this condenser amounts only to 35,000 ohms.

10 This radiation may be reduced by employing two screen grids 6 and 6' instead of one. This should, however, be regarded only as an approximation to complete freedom from radiation. The supply conductor 3' should be completely 15 screened in the interior of valve 4 against internal coupling capacities by means of a shield 16.

A complete elimination of radiation without employing a second screen grid 6' is effected by 20 applying a neutralizing oscillation to the antenna 1. An adjustable fraction of the oscillations produced by local oscillator 8 and which is at reverse phase to that at grid 12, is taken through a very small adjustable condenser 18 and supplied 25 to the control grid terminal 19. The very small neutralization capacity 18 is advantageously produced by a screened coupling condenser. An earthed plate 18a is inserted between the coupling plates of 18.

The oscillator circuit valve 8 and oscillating circuit 10, 11 may be compared with a capacitatively coupled three-point-circuit (the German term is: "Dreipunktschaltung") which represents a capacitative potentiometer circuit by 35 which in case of short waves the reverse phase of auxiliary potential is best attained. The inherent earth capacities 13 and 14 of the oscillating circuit 10, 11 are authoritative for the anode-cathode potential and the grid-cathode potential 40 of valve 8; and these operating potentials are opposed in phase. Since capacities 13 and 14 are generally quite small (order of magnitude 10 cm.) the circuit can oscillate only at high operating frequencies; in case of very high frequencies the required phase opposition is attained most accurately. The state of reverse phase between anode and grid of the oscillatory system is also improved by connecting the anode supply conductor 15 to the midpoint of the oscillation coil 50 11. The oscillator system begins to oscillate as soon as the capacitative potential across the earth capacities is sufficiently high.

A suitable constructional embodiment of the circuit of Fig. 1 is illustrated in Fig. 2. The chas- 55

sis of the frequency changing stage of the receiver is made of metal and indicated by 20. The chassis is closed on all sides and earthed. One plate of condenser 18 is connected to the 5 oscillation circuit 10, 11 which is located in the interior of the oscillator box 20. The other plate of condenser 18 is connected to the antenna 1 (either directly as shown in Fig. 2, or via condenser 2 as shown in Fig. 1. In the latter case 10 the value of the coupling capacity 18 is greater). The grid choke coil 21 supplies grid bias to the control grid 3 through a very short conductor 22, and is also connected to coupling condenser 2 and thus the antenna 1. The intermediate 15 plate 18a of condenser 18 partly covers the aperture 35 in the portion of the chassis separating the plates of condenser 18 and its position is adjusted by the screw 23. The neutralizing oscillations pass through conductor 24 to antenna 1. With complete shielding of 18 by means of 20 18a, the antenna 1 radiates on account of the harmful capacity between the oscillation grid 7 and the control grid 3 already mentioned. By slowly increasing the effective aperture 35 in the 25 upper surface of 20 by moving the plate 18a, the coupling via condenser 18 is increased until a point is found at which the radiation from the antenna is neutralized.

After the neutralization adjustment has been 30 found it is made independent of fluctuations and alterations of the partial capacities of the antenna on the circuit by placing an earthed shield 25 over the entire circuit and leading the antenna connection in through a small hole. All the battery feed conductors leading into the housing 20 are provided with high frequency series chokes and earthing condensers.

The process of neutralizing by means of a 35 reverse phase auxiliary potential derived from the oscillator is not limited to the circuits of Figs. 1 and 2. For example, the reverse phase potential may be produced, as shown in Fig. 3, by means of an auxiliary winding 26 which is inductively coupled to the oscillator coil 11. The auxiliary 40 oscillations obtained in this way will be exactly at reverse phase to those applied to grid 3 via the inter-electrode capacity 29 so long as the resonant frequency of winding 26 is higher than the oscillation frequency of circuit 10, 11. Also 45 the tuning system which is connected to the control grid 3, may be otherwise than as shown in Figs. 1 and 2. For example, as shown in Fig. 3, an oscillation circuit 27, 28 may be employed for antenna tuning without disturbing the neutralization because the neutralization is free from 50 phase displacement. Also the coupling of antenna 1 to grid 3 may be made inductive without disturbing the action of the neutralizing process. Finally the neutralizing oscillations may 55 also be introduced into the tuning circuit 27, 28 by means of an inductive coupling.

The invention is especially suitable for use in 60 radio receivers operating on ultra-short waves which may be modulated e. g. with speech currents or television signals.

I claim:

1. In a heterodyne receiver for the use in short 65 wave art and ultra-short wave art, means for preventing radiation of the locally generated oscillation by the receiver aerial, a mixing tube having a cathode, a control grid, at least one screen grid, an oscillation grid, a second screen grid and an anode, arranged in the order named, an aerial circuit coupled with said control grid, 70 an oscillatory tube having an anode, a cathode, and a grid, a neutralizing circuit for compensating the undesired coupling between the control- 75

and a grid, a neutralizing circuit for compensating the undesired coupling between the control- and oscillation-grid of said mixing tube effected by the inherent capacity between said two grids, said neutralizing circuit consisting of a variable 5 condenser connected between the control grid of said mixing tube and the grid of said oscillator tube so that a neutralizing potential of opposite phase with respect to the original oscillatory potential is led from an electrode of said oscillatory 10 tube to the control grid of said mixing tube and the aerial circuit respectively the anode of said oscillator tube being coupled to the oscillation grid of said mixing tube.

2. In a heterodyne receiver for the use in short 15 wave art and ultra-short wave art, means for preventing radiation of the locally generated oscillation by the receiver aerial, a mixing tube having a cathode, a control grid, at least one screen grid, an oscillation grid, a second screen 20 grid and an anode, arranged in the order named, an aerial circuit coupled with said control grid, an oscillatory tube having an anode, a cathode, and a grid, a neutralizing circuit for compensating the undesired coupling between the control- 25 and oscillation-grid of said mixing tube effected by the inherent capacity between said two grids, a variable neutralizing condenser connected in the coupling circuit between the control grid of said mixing valve and the anode or grid of said 30 oscillator tube, so that a neutralizing potential of opposite phase with respect to the original oscillatory potential is led from the anode of said oscillator tube to the control grid of said mixing tube and the aerial circuit respectively the 35 control grid of said oscillatory tube being coupled to the oscillation grid of said mixing tube.

3. In a heterodyne receiver for the use in short 40 wave art and ultra-short wave art, means for preventing radiation of the locally generated oscillation by the receiver aerial, a mixing tube having a cathode, a control grid, at least one screen grid, an oscillation grid, a second screen grid and an anode, arranged in the order named, an aerial circuit coupled with said control grid, 45 an oscillatory tube having an anode, a cathode, and a grid, a neutralizing circuit for compensating the undesired coupling between the control- and oscillation-grid of said mixing tube effected by the inherent capacity between said two grids, 50 said neutralizing circuit consisting of a variable condenser connected between the control grid of said mixing tube and the anode of said oscillator tube so that a neutralizing potential of opposite phase with respect to the original oscillatory potential is led from an electrode of said oscillatory tube to the control grid of said mixing tube and the aerial circuit respectively, the control grid of said oscillatory tube being coupled to the oscillator grid of said mixing tube, 55 said neutralizing condenser being constructed as a screened condenser having a metal sheet which may be inserted between its two electrodes in more or less large extension.

4. In a heterodyne receiver for the use in short 60 wave art and ultra-short wave art, means for preventing radiation of the locally generated oscillation by the receiver aerial, a mixing tube having a cathode, a control grid, at least one screen grid, an oscillation grid, a second screen 65 grid and an anode arranged in the order named, an aerial circuit coupled with said control grid, an oscillatory tube having an anode, a cathode, and a grid, a neutralizing circuit for compensating the undesired coupling between the control- 70 and oscillation-grid of said mixing tube effected by the inherent capacity between said two grids, a variable neutralizing condenser connected between the control grid of said mixing tube and the anode of said oscillator tube so that a neutralizing potential of opposite phase with respect to the original oscillatory potential is led from an electrode of said oscillatory tube to the control grid of said mixing tube and the aerial circuit respectively, the control grid of said oscillatory tube being coupled to the oscillator grid of said mixing tube, 75 said neutralizing condenser being constructed as a screened condenser having a metal sheet which may be inserted between its two electrodes in more or less large extension.

and oscillation-grid of said mixing tube effected by the inherent capacity between said two grids, said neutralizing circuit consisting of a variable condenser connected between the control grid of said mixing tube and the grid of said oscillator tube, so that a neutralizing potential of opposite phase with respect to the original oscillatory potential is led from an electrode of said oscillatory tube to the control grid of said mixing tube 5 and the aerial circuit respectively, the anode of said oscillator tube being coupled to the oscillation grid of said mixing tube said oscillator tube and also said mixing tube with their appertaining coupling element being surrounded by an 10 earthed screening means, which is closed on all sides and within which all part-capacities are rendered invariable and out of which there is passed only the aerial lead.

5. In a heterodyne receiver for the use in short 20 wave art and ultra-short wave art, means for preventing radiation of the locally generated oscillation by the receiver aerial, a mixing tube having a cathode, a control grid, at least one screen grid, an oscillation grid, a second screen grid and an anode arranged in the order named, an aerial circuit coupled with said control grid, an oscillatory tube having an anode, a cathode, and a grid, a neutralizing circuit for compensating the undesired coupling between the control- 25 and oscillation-grid of said mixing tube effected by the inherent capacity between said two grids, a variable neutralizing condenser connected between the control grid of said mixing valve and the anode of said oscillator tube, so that a neutralizing potential of opposite phase with respect to the original oscillatory potential is led from an electrode of said oscillatory tube to the control grid of said mixing tube and the aerial circuit respectively, said oscillator tube and also said mixing tube with their appertaining coupling element being surrounded by an earthed screening means, which is closed on all sides and within which all part-capacities are rendered invariable and out of which there are passed only the aerial lead and the feed lines, said feed lines are provided with series chokes and are earthed capacitatively.

6. In a heterodyne receiver for the use in short 50 wave art and ultra-short wave art, means for preventing radiation of the locally generated oscillation by the receiver aerial, a mixing electrode system having a cathode, a control grid, at least one screen grid, an oscillation grid, a second screen grid and an anode, arranged in the order named, an aerial circuit coupled with said control grid, an oscillatory electrode system having an anode, a cathode, and a grid, a neutralizing circuit for compensating the undesired coupling between the control- and oscillation grid 55 of said mixing electrode system effected by the inherent capacity between said two grids, a variable neutralizing condenser connected in the coupling circuit between the control grid of said mixing electrode system and the anode of said oscillator electrode system, so that a neutralizing potential of opposite phase with respect to the original oscillatory potential is led from an electrode of said oscillatory electrode system to the control grid of said mixing electrode system and the aerial circuit respectively, the control grid 60 of said oscillatory tube being coupled to the oscillation grid of said mixing tube, said oscillator electrode system and the electrode of the mixing electrode system are arranged in the same tube.

7. In a heterodyne receiver for the use in short wave art and ultra-short wave art, means for preventing radiation of the locally generated oscillation by the receiver aerial, a mixing tube having a cathode, a control grid, at least one screen grid, an oscillation grid, a second screen grid and an anode, arranged in the order named, an aerial circuit coupled with said control grid, an oscillatory tube having an anode, a cathode, and a grid, a neutralizing circuit for compensating the undesired coupling between the control- and oscillation-grid of said mixing tube effected by the inherent capacity between said two grids, a variable neutralizing condenser connected in the coupling circuit between the control-grid of 15 said mixing tube and the grid of said oscillator tube, so that a neutralizing potential of opposite phase with respect to the original oscillatory potential is led from the anode of said oscillatory tube to the control grid of said mixing tube and the aerial circuit respectively, the anode of said oscillator tube being coupled to the oscillation grid of said mixing tube, said neutralizing condenser being constructed as a screened condenser having a metal sheet which may be inserted between its two electrodes in more or less large extension.

8. In a heterodyne receiver for the use in short 20 wave art and ultra-short wave art, means for preventing radiation of the locally generated oscillation by the receiver aerial, a mixing tube having a cathode, a control grid, at least one screen grid, an oscillation grid, a second screen grid and an anode, arranged in the order named, an aerial circuit coupled with said control grid, an oscillatory tube having an anode, a cathode, and a grid, a neutralizing circuit for compensating the undesired coupling between the control- and oscillation-grid of said mixing tube effected by the inherent capacity between said two grids, 25 said neutralizing circuit consisting of a variable condenser connected between the control grid of said mixing tube and the anode of said oscillator tube so that a neutralizing potential of opposite phase with respect to the original oscillatory potential is led from an electrode of said oscillatory tube to the control grid of said mixing tube and the aerial circuit respectively, the control grid of said oscillatory tube being coupled to the oscillation grid of said mixing tube, said neutralizing condenser being constructed as a screened condenser having a metal sheet which may be inserted between its two electrodes in more or less large extension, said oscillator tube and also said mixing tube with their appertaining circuit elements being surrounded by an earthed screening means, which is closed on all sides and within which all part-capacities are rendered invariable and out of which there is passed only the aerial lead.

9. In a heterodyne receiver for the use in short 30 wave art and ultra-short wave art, means for preventing radiation of the locally generated oscillation by the receiver aerial, a mixing tube having a cathode, a control grid, at least one screen grid, an oscillation grid, a second grid and an anode, arranged in the order named, an aerial circuit coupled with said control grid, an oscillatory tube having an anode, a cathode, and a grid, a neutralizing circuit for compensating the undesired coupling between the control- and oscillation-grid of said mixing tube effected by the inherent capacity between said two grids, said neutralizing circuit consisting of a variable condenser connected between the control grid of said mix- 35

ing tube and the grid of said oscillator tube so that a neutralizing potential of opposite phase with respect to the original oscillatory potential is led from an electrode of said oscillatory tube to the control grid of said mixing tube and the aerial circuit respectively, the anode of said oscillator tube being coupled to the oscillation grid of said mixing tube, said oscillator electrode system and the electrode of the mixing electrode system are arranged in the same tube.

10. In a heterodyne receiver for the use in short wave art and ultra-short wave art, means for preventing radiation of the locally generated oscillation by the receiver aerial, a mixing tube having a cathode, a control grid, at least one screen grid, an oscillation grid, a second screen grid and an anode arranged in the order named, an aerial circuit coupled with said control grid, an oscillatory tube having an anode, a cathode, and a grid, a neutralizing circuit for compensating the undesired coupling between the control-

and oscillation-grid of said mixing tube effected by the inherent capacity between said two grids, said neutralizing circuit consisting of a variable condenser connected between the control grid of said mixing tube and the grid of said oscillator tube so that a neutralizing potential of opposite phase with respect to the original oscillatory potential is led from an electrode of said oscillatory tube to the control grid of said mixing tube and the aerial circuit respectively, the anode of said oscillator tube being coupled to the oscillation grid of said mixing tube, said oscillator tube and also said mixing tube with their appertaining circuit elements being surrounded by an earthed screening means, which is closed on all sides and within which all part-capacities are rendered invariable and out of which there is passed only the aerial lead and the feed lines, said feed lines are provided with series chokes and are earthed capacitatively.

KURT SCHLESINGER.
